CLAIM

The ornamental design for a jacket hood, as shown and described.

DESCRIPTION

FIG. 1 is a front perspective view of a jacket hood;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is another front perspective view thereof.

The evenly spaced broken lines depict portions of the jacket that form no part of the claimed design. The dash-dot-dash broken lines depict boundary lines for the jacket hood that form no part of the claimed design.

1 Claim, 7 Drawing Sheets
